ABSTRACT OF THE DISCLOSURE

A microwave generator for developing a harmonic such as the second harmonic of a signal input frequency. The harmonic generator utilizes an element exhibiting ferrimagnetic resonance such as a piece of ferrite or else a ferroelectric element. The ferrite element is so dimensioned that it will resonate electromagnetically at the desired harmonic frequency. On the other hand, a magnetic field applied to the ferrite element has a magnitude to provide gyromagnetic resonance at the fundamental frequency. As a result, substantially all the energy at the desired harmonic is contained in the ferrite element.

BACKGROUND OF THE INVENTION

This invention relates generally to microwave generators, and particularly relates to a harmonic generator having a relatively large energy output at a desired harmonic frequency.

Harmonic generators at microwave frequencies are well known in the art. They usually include a circuit such as a chamber or waveguide resonant at the fundamental or input frequency as well as at the desired output frequency which is a harmonic of the input frequency. It can be calculated that in that case the output power is given by the following equation:

$$P_{2\omega} \approx \frac{1}{2} \frac{P_{in}^2 F^2}{R_{2\omega}} \quad (1)$$

wherein P_{in} is the input power, F is a figure of merit of the material, such as a ferrite, ω is the angular input frequency, $P_{2\omega}$ is the desired output power at the second harmonic, and

$R_{2\omega}$ is a quantity which must be minimized to achieve maximum output power.

In turn, the quantity $R_{2\omega}$ may be defined as follows:

$$R_{2\omega} = \frac{2\omega U}{Q_{2\omega} h_{2\omega}^2} \quad (2)$$

wherein $h_{2\omega}$ is the amplitude of the magnetic field at the second harmonic frequency in the resonant structure,

U is the energy stored in the electromagnetic field at the second harmonic frequency corresponding to the magnetic field $h_{2\omega}$, and

$Q_{2\omega}$ is the unloaded Q of the resonant circuit at the second harmonic frequency.

The above formulas have been obtained by equalizing the power generated to the power lost in the harmonic generator at the harmonic frequency. From this, Formulas 1 and 2 may be derived.

In order to accomplish harmonic generation with ferrites, it has previously been suggested to use a resonant cavity of relatively large size containing a piece of ferrite of very small size. The reason for the small ferrite is that a large piece disturbs the field configuration to the point of rendering the scheme ineffective.

The scheme of a large resonator and a small specimen of ferrite is contrary to what is desired, according to

2

Equations 1 and 2. For there one sees a quantity $R_{2\omega}$ which should be as small as possible for maximum power output and at constant frequency ω and constant resonator Q . $R_{2\omega}$ is proportional to the energy stored in the electromagnetic field when the maximum amplitude of the h -component electromagnetic field is $h_{2\omega}$. Thus, $R_{2\omega}$ is minimized (and $P_{2\omega}$ is maximized) when U is minimized. And to minimize U , we minimize the resonator volume.

It is accordingly an object of the present invention to provide a harmonic generator at microwave frequencies which will deliver a harmonic output frequency at a relatively high energy.

Another object of the present invention is to provide a microwave frequency doubler wherein the energy at the desired second harmonic frequency is substantially entirely contained in a ferrite element.

A further object of the present invention is to provide a microwave frequency multiplier which may be realized with either an isotropic or anisotropic ferrite element.

SUMMARY OF THE INVENTION

A microwave frequency multiplier in accordance with the present invention includes signal input means tuned to the frequency of the desired input signal. An element which exhibits ferrimagnetic or ferroelectric resonance such as a ferrite element is disposed in the resonant chamber. Such an element normally has dielectric properties at harmonics of the signal frequency. The ferrite element is so dimensioned that it will resonate at the desired harmonic frequency. In other words, its dimensions are such as to establish a standing electromagnetic wave at the desired harmonic frequency which is substantially contained in the element. On the other hand, a steady magnetic field is established through the element which has a magnitude to provide gyromagnetic resonance of the ferrite element at the signal frequency.

The output wave at the desired harmonic such as the second harmonic of the fundamental frequency may be obtained by any suitable output circuit means. This may, for example, consist of a loop coupled to the electromagnetic field at the desired harmonic of the signal frequency developed by the element. Alternatively, a tuned waveguide may be used as the output circuit means.

The novel features that are considered characteristic of this invention are set forth with particularity in the appended claims. The invention itself, however, both as to its organization and method of operation, as well as additional objects and advantages thereof, will best be understood from the following description when read in connection with the accompanying drawing.

BRIEF DESCRIPTION OF THE DRAWING

FIG. 1 is a schematic top plan view of a microwave frequency doubler in accordance with the present invention, utilizing a disk of isotropic ferrite:

FIG. 2 is a side elevational view taken on lines 2—2 of FIG. 1 and illustrating particularly the ferrite in its resonant chamber and the output loop probe:

FIGS. 3a and 3b are respectively a top plan and side elevational view of the ferrite disk of FIGS. 1 and 2 illustrating the dipole resonance thereof;

FIG. 4 is a schematic top plan view taken in lines 4—4 of FIG. 5 of another embodiment of a microwave frequency doubler embodying the invention and utilizing an anisotropic ferrite rod;

FIG. 5 is a side elevational view of the frequency doubler of FIG. 4;

FIG. 6 is an enlarged side view of the anisotropic ferrite rod and its end plates, showing particularly the magnetic field at the second harmonic frequency; and

FIG. 7 is a side elevational view similar to that of FIG. 6, of a modification of the frequency doubler of FIG. 4 utilizing both a ferrite and a dielectric rod.

DESCRIPTION OF THE PREFERRED EMBODIMENTS

Referring now to the drawing wherein like elements are designated by the same reference characters, and particularly to FIGS. 1 and 2, there is illustrated a microwave frequency multiplier embodying the present invention. The embodiment of FIGS. 1 and 2 is based on the fact that a specimen of material exhibiting ferrimagnetic resonance can be made to act as a dielectric at a harmonic of the fundamental frequency, and hence can be made into a harmonic resonant. The embodiment of the invention of FIGS. 1 and 2 utilizes isotropic ferrite.

There is provided a waveguide 10 which is provided with a conventional tuning device, such as one or more tuning screws 9 that cause virtually all of the input power at the frequency ω to be absorbed by a ferrite element 11. The input signal is impressed by a source not shown on the waveguide 10. This is indicated by P_{in} representing the input power at the angular frequency ω . If desired, a resonant chamber may be used; however, it may not be necessary to use a resonant chamber provided the ferrite element is comparatively large compared to the size of the resonant structure.

A disk 11 of a material which exhibits ferrimagnetic resonance such as a piece of ferrite having isotropic properties may be used. It is also feasible, however, to utilize instead an element having ferroelectric properties. The ferrite may, for example, consist of yttrium iron garnet. Two magnets 12 and 13, having magnetic north and south poles as shown, are disposed to generate a magnetic field H_{dc} which extends at right angles to the axis of ferrite disk 11 as shown by the dashed lines 14. Preferably the magnitude of the steady magnetic field H_{dc} developed by the magnets 12 and 13 may be adjusted to provide magnetic resonance in the ferrite disk 11 at the desired input frequency.

A loop probe 15 is disposed in the neighborhood of disk 11 and may be a magnetic probe as shown for coupling to the magnetic field at the harmonic frequency developed about the ferrite disk 11. The wires 16 of the probe 15 extend through waveguide 10 through a suitable aperture 17.

Preferably, as shown in FIG. 2, the flat ends of the disk 11 are covered by a pair of conductive plates 18.

In order to explain the operation of the frequency doubler of FIGS. 1 and 2, reference is also made to FIGS. 3a and 3b. As explained before, the steady magnetic field H_{dc} extends at right angles to the axis of the disk 11 and through the flat ends of the ferrite disk 11. On the other hand, the alternating magnetic field h_{ω} developed by the micro-wave input signal also extends in the flat plane of the disk 11 as shown by the dashed lines 20. Accordingly the two magnetic fields H_{dc} and h_{ω} are orthogonal to each other.

It should be noted that the strength or magnitude of the magnetic field H_{dc} is such as to provide gyromagnetic resonance of the ferrite disk 11 at the input or signal frequency. Since the gyromagnetic resonance extends over only a small frequency range, it will be evident that there is no gyromagnetic resonance at harmonics of the fundamental or signal input frequency. Accordingly the ferrite disk 11 behaves like a dielectric at harmonics of the fundamental frequency.

Further in accordance with the invention the ferrimagnetic disk 11 is so proportioned that it is in electromagnetic resonance at 2ω , that is, at twice the fundamental frequency or some other desired harmonic frequency. The magnetic field lines for $h_{2\omega}$ are also shown in FIG. 1 by dashed lines 21. It will be seen that the magnetic field lines at the second harmonic frequency are orthogonal to the magnetic field h_{ω} and hence parallel

to the steady magnetic field at the flat surface of ferrite disk 11. It should also be noted that the second harmonic magnetization $m_{2\omega}$ also appears parallel to H . The harmonic magnetization $m_{2\omega}$ is proportional to h_{ω} where h_{ω} is the field intensity at the input frequency. It is due to this $m_{2\omega}$, that the second harmonic magnetization acts as a source at the frequency 2ω .

The second harmonic magnetization $m_{2\omega}$ excites a resonance at the second harmonic frequency so that a standing electromagnetic wave at the second harmonic frequency is set up. As stated before, the loop 15 couples to the magnetic field. However it should be emphasized that the use of an electric probe which couples to the electric field existing at right angles to the magnetic field is also feasible.

The resonance which is excited by the second harmonic magnetization is the dipolar mode as shown in FIGS. 3a and 3b. Here the electric field vector is indicated by E and the magnetic field by h .

It will now be apparent that the metallic plates 18 which cover the outer flat surfaces of the disk 11 serve the purpose to limit the electric field and to allow resonance in the so-called dipolar mode.

In order to cause the disk 11 to resonate at the second harmonic magnetization, its diameter D is determined by the following relation:

$$D \approx \frac{1.84}{\pi} \frac{\lambda_0}{\sqrt{\epsilon_r}} \quad (3)$$

wherein λ_0 is the free-space wavelength of the second harmonic frequency within the ferrite, and ϵ_r is the dielectric constant of the ferrite at the resonant frequency.

To summarize again, the embodiment of FIGS. 1 and 2 utilizes a magnetic field having such a magnitude as to permit the ferrite disk 11 to have gyromagnetic resonance at the signal frequency. On the other hand, the disk 11 is so dimensioned to establish a standing electromagnetic wave at the desired harmonic of the input signal frequency. This may, for example, be the dipolar mode shown in FIGS. 3a and 3b, in which case the diameter is determined by Formula 3.

Referring now to FIGS. 4 through 6, there is illustrated another embodiment of a microwave frequency multiplier in accordance with the present invention. This frequency multiplier utilizes a rod of anisotropic ferrite where the length of the cylinder or rod determines the dipolar dielectric mode which causes the ferrite to resonate at the desired harmonic frequency.

Thus there is an input waveguide 10 which is again tuned to the signal input frequency. This is indicated in FIG. 4 by P_{in} indicating the input power at the angular input frequency ω . Again the two magnets 12 and 13 providing respectively north and south poles as shown are disposed in the manner shown in FIG. 5. A rod or cylinder 25 of anisotropic planar ferrite material is disposed in the waveguide 10 in such a manner that the steady magnetic field H_{dc} is parallel to the axis of the rod 25. The magnitude of the magnetic field is again such as to provide gyromagnetic resonance of the rod 25 at the signal input frequency.

The rod 25 is preferably cut in such a manner that the easy plane of magnetization is parallel to the axis of the rod, that is, parallel to H_{dc} . The magnetic field h_{ω} at the signal input frequency is shown by the dashed lines 26 and extends at right angles to the axis of the rod through the flat ends of the rod.

As shown particularly in FIG. 6, the flat surfaces of the rod 25 may be covered again with metallic plates 27. Again their purpose is to terminate the electric field within the rod 25.

The second harmonic magnetization $m_{2\omega}$ is now also parallel to the axis of the rod 25 and the resulting magnetic field $h_{2\omega}$ is shown in FIG. 6 at 28. Preferably the length of the rod 25 is one-half of the guide wavelength

of this dipolar dielectric mode set up in the rod. Again we must consider the ferrite as a dielectric at the harmonic of the fundamental frequency.

The desired output wave at the harmonic such as the second harmonic of the signal frequency may be coupled out by a waveguide 30 which is tuned to the desired second harmonic. This is indicated by P_{out} at 2ω . A coupling hole 31 couples the ferrite rod 25 to the output waveguide 30. However, it will be understood that the output power may be obtained in any other suitable manner.

Accordingly it will be evident that use is now made of the dipolar propagating dielectric mode of the ferrite rod 25 at the desired harmonic. Again the gyromagnetic resonance at the signal frequency is determined by the strength of the magnetic field H_{dc} . On the other hand, the ferrite 15 which now is a dielectric at any harmonic frequency is made to resonate at the desired harmonic frequency by making the length of the cylinder 25 approximately one-half of the guide wavelength of the dipolar propagating dielectric mode. In other words, this is one-half the wave- 20 length at the desired harmonic frequency in the ferrite.

While the embodiment of the invention shown in FIG. 6 shows a basic scheme for a ferrite resonator, the modification of FIG. 7 may be preferred. If the magnetic field h_ω driving the ferrite is everywhere in phase across the ferrite material, then the harmonic magnetization $m_{2\omega}$ will also be in the phase across the material. The dipolar mode of a half-wave resonator however has a harmonic magnetic field $h_{2\omega}$ of opposite phase at its two outer metallic ends. In view of this situation, not much power is generated at the second harmonic frequency unless half of the rod is deactivated magnetically. This can be achieved with the embodiment shown in FIG. 7. Here the ferrite rod 25 is combined with a dielectric rod 35 which preferably has the same diameter. Again the two opposed or free ends are covered by a pair of metallic plates 27 as shown. All that is needed is to use the structure of FIG. 7 for that shown in FIG. 6 and to insert it into the waveguide 10 as shown in FIGS. 4 and 5.

There has thus been disclosed a microwave frequency multiplier such as a frequency doubler making use of a material having ferrimagnetic resonance. This may be a piece of ferrite of either isotropic or anisotropic properties. The magnetic field is so adjusted that it causes ferrimagnetic resonance of the ferrite element at the fundamental or signal input frequency. A desired harmonic is set up in the ferrite by dimensioning it so that a standing electromagnetic wave is set up in the element at a selected harmonic of the fundamental frequency. Since substantially all of the harmonic energy is now contained in the ferrite element, the energy output at the desired harmonic is substantially higher than that of prior art devices.

What is claimed is:

1. A microwave frequency doubler comprising: an input waveguide tuned to the frequency of a desired input signal, said waveguide being not resonant at the second harmonic of said input signal frequency; a disk of isotropic ferrite disposed in said waveguide and having a diameter selected to resonate at said second harmonic; conductive plates covering the flat surfaces of said disk; means for establishing a steady magnetic field substantially at right angles to the axis of said disk, said magnetic field having a magnitude to provide gyro-

magnetic resonance of said disk at said input signal frequency; and a loop probe coupled to the electromagnetic field at said harmonic of said input signal frequency for deriving the doubled frequency output wave.

5 2. A frequency doubler as defined in claim 1 wherein said loop probe is a magnetic probe coupled to the magnetic field at said harmonic frequency.

3. A microwave frequency doubler comprising: a signal input waveguide tuned to the frequency of a desired input signal, said input waveguide having dimensions smaller than necessary to cause said waveguide to resonate at the second harmonic of said input frequency;

10 a rod disposed in said waveguide, said rod consisting of anisotropic ferrite, said rod having dimensions selected to cause said element to resonate at said second harmonic and said dimensions being of the same order of magnitude as those of said waveguide; conductive plates covering the flat surfaces of said ferrite rod;

means for establishing a steady magnetic field substantially parallel to the axis of said rod, said magnetic field having a magnitude to provide gyromagnetic resonance of said element at said input signal frequency; and

output circuit means coupled to said ferrite rod for deriving the doubled frequency output wave.

4. A frequency doubler as defined in claim 3 wherein 15 said ferrite rod has a length substantially one half wavelength of the guide wavelength at said harmonic frequency.

30 5. A frequency doubler as defined in claim 3 wherein said anisotropic ferrite is cut so that the easy plane of magnetization is parallel to the axis thereof.

35 6. A frequency doubler as defined in claim 3 wherein a rod of dielectric is disposed adjacent to said ferrite rod, both of said rods having substantially the same diameter.

7. A frequency doubler as defined in claim 6 wherein 20 the outer flat surfaces of said ferrite rod and of said dielectric rod are covered by conductive plates.

8. A frequency doubler as defined in claim 6 wherein 25 said ferrite rod has a length substantially one half wavelength of the guide wavelength at said harmonic frequency.
